(57) **CLAIM**

The ornamental design for a grill spray bottle, as shown and described.

DESCRIPTION

FIG. 1 is a top and right front perspective view of a grill spray bottle;

FIG. 2 is a front elevational view thereof;

FIG. 3 is a rear elevational view thereof;

FIG. 4 is a left side elevational view thereof, the right side elevational view being a mirror image of the side view shown;

FIG. 5 is a top plan view thereof; and;

FIG. 6 is a bottom plan view thereof.

The broken lines are included for the purpose of illustrating portions of the grill spray bottle that form no part of the claimed design.
